BREECH MECHANISM OF ORDNANCE.

1,298,020.

Specification of Letters Patent. Patented Mar. 25, 1919.

Application filed June 21, 1917. Serial No. 176,113.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Breech Mechanism of Ordnance, 10 of which the following is a specification.

This invention relates to the breech mechanism of ordnance, such as howitzers, that are adapted to be loaded at high angles of elevation and in which the pivotal axis of the breech screw carrier is vertical when the gun is horizontal, the chief object being to provide means for balancing the weight of the breech screw and its swinging carrier during the opening and closing movements 20 with the gun at the loading angle so as to facilitate the operation of the breech mechanism. To accomplish this object, it is necessary that the falling moment of the swinging mass (the screw and the carrier) should be practically neutralized by the balancing means at any point of the swing-out movement about the hinge pin and if the balancing means comprise a spring it will at the same time be necessary that the total 30 work done by the swinging mass shall be balanced by the total work done in energizing the spring. These conditions being obtained the breech mechanism can then be operated at high angles of elevation as 35 easily as the breech mechanism of a gun loaded at the horizontal.

In meeting the above requirements the main difficulty to be overcome resides in the fact that the swinging mass (the breech 40 screw and carrier) exerts a maximum falling moment at the commencement of the swinging out movement, which moment gradually diminishes to zero when the center of gravity of the mass reaches a position 45 directly behind the carrier hinge pin. A secondary difficulty is the inevitable increase in the load of the balancing spring while the falling moment of the mass is diminishing to zero.

According to the present invention the balancing spring is arranged to exert upon the breech screw carrier through a suitably formed cam, during the opening and closing movements of the carrier when the gun

is at the loading angle, a turning moment 55 which will vary substantially in accordance with the falling moment of the carrier and its parts. For this purpose the spring may be of the compression type and may be situated vertically within the hinge portion of 60 the breech screw carrier, this spring being held under a considerable initial compression (the amount being determined by the weight of the swinging parts and the loading angle of elevation of the gun) by a 65 central compression bolt. This spring compressing bolt may be provided with conical anti-friction rollers which bear against suitable stationary cam surfaces so arranged as to give (in conjunction with the load on the 70 spring) the necessary turning moment upon the carrier for counteracting its falling tendency at any point of the swinging movement.

In order that the said invention may be 75 clearly understood and readily carried into effect we will describe the same more fully with reference to the accompanying drawings, in which:

Figure 1 is a rear elevation showing the 80 breech end of a gun provided with a constructional form of the improvements.

Fig. 2 is a side elevation on an enlarged scale of the lower part of the breech screw carrier of Fig. 1.

Fig. 3 is a vertical section taken on the line 1, 1 of Fig. 2.

Fig. 4 is an inverted plan of Fig. 3.

Fig. 5 is a development of the cam surfaces.

Fig. 6 is a side elevation showing a modified detail of construction, and

Fig. 7 is a section taken on the line 2, 2 of Fig. 6.

A is the hinge portion of the breech screw 95 carrier pivotally supported at its upper and lower ends in lugs B, B' on the breech ring of the gun as is well understood. C is the balancing spring and C' is the spring compressing bolt. D, D are the stationary cam 100 surfaces and c, c are the conical rollers carried by the bolt C' for engaging with these cam surfaces.

The bolt C' is shown as of inverted T formation, the horizontal or transverse arm 105 c' being provided at its ends with the aforesaid rollers c, c. The cam surfaces D, D are formed on the underside of the lower lug B.

The arm c' of the compressing bolt C' is guided, during the axial movements of the bolt, in a slot e formed in a bush E fitted into the lower part of the hinge portion A of the carrier, this bush taking the load of the spring in such a manner that the removal of a retaining screw e' enables the bush together with the spring and the compressing bolt to be removed intact. The bush is attached by keys or otherwise to the hinge portion A of the carrier to insure that the correct relative positions of these parts shall be obtained in assembling. The downward thrust of the balancing spring is preferably taken by the usual ball bearing provided on the upper hinge lug B' of the breech ring for supporting the dead weight of the carrier. The spring compressing bolt C' is provided at its upper end with an adjusting nut C^2 to enable the load on the spring to be varied in accordance with requirements.

It will be seen from the above description and from inspection of Fig. 5 (in which figure the rollers c, c are shown in the position they occupy when the breech is closed) that when the carrier commences to open and the spring compressing bolt also turns, the said rollers will begin to move along the cam surfaces D, D and the spring C will exert upon the carrier, through the bolt C' , the rollers c, c and the cam surfaces D, D , a turning moment, in opposition to that due to the swinging movement, which will be greatest at the commencement of the opening and will decrease to zero when the rollers reach the position indicated by broken lines in Fig. 5 at which time the carrier lies at right angles to the gun or at the dead center of its movement; further movement of the carrier beyond the dead center to its fully open position, will cause the rollers to engage with portions of the cam surfaces that are slightly inclined in the reverse direction and the spring will then exert a turning movement on the carrier in the reverse direction to that above stated and resiliently retain the said carrier in its fully open position.

In Figs. 6 and 7 the arm c' is provided with rollers c^2, c^2 for engaging with the aforesaid slot e in the bush E . In this case these rollers and also the rollers c, c are mounted on a spindle c^2 passing through lugs on the ends of the arms c' as shown.

What we claim and desire to secure by Letters Patent of the United States is:—

1. In breech mechanism for ordnance loaded at high angles of elevation, the combination with the breech screw carrier having its pivotal axis inclined to the vertical when the gun is being loaded, of a balancing spring and a cam for causing said

spring to exert upon the carrier a turning moment which will vary substantially in accordance with the falling moment of the carrier during its opening and closing movements.

2. In breech mechanism for ordnance loaded at high angles of elevation, the combination with the breech screw carrier having its pivotal axis inclined to the vertical when the gun is being loaded, of a balancing spring of the compression type, a compressing bolt for co-operating with said spring, rollers carried by said bolt and a cam upon which said rollers run during the opening and closing movements of the carrier to vary the energization of said spring for balancing the carrier.

3. In breech mechanism for ordnance loaded at high angles of elevation, the combination with the breech screw carrier having its pivotal axis inclined to the vertical when the gun is being loaded, of a balancing spring of the compression type, a compressing bolt for co-operating with said spring, rollers carried by said bolt and a cam upon which said rollers run during the opening and closing movements of the carrier to vary the energization of said spring for balancing the carrier and for resiliently holding said carrier in its fully open position.

4. In breech mechanism for ordnance loaded at high angles of elevation, the combination with the breech screw carrier having its pivotal axis inclined to the vertical when the gun is being loaded, of a balancing spring of the compression type having its axis extending in the same direction as the pivotal axis of the carrier, and means for causing said spring to exert upon the carrier a turning moment which will vary substantially in accordance with the falling moment of the carrier during its opening and closing movements.

5. In breech mechanism for ordnance loaded at high angles of elevation, the combination with the breech screw carrier having its pivotal axis inclined to the vertical when the gun is being loaded, of a balancing spring of the compression type having its axis substantially coincident with the pivotal axis of the carrier, and means for causing said spring to exert upon the carrier a turning moment which will vary substantially in accordance with the falling moment of the carrier during its opening and closing movements.

ARTHUR TREVOR DAWSON.
GEORGE THOMAS BUCKHAM.
